[57] CLAIM

The ornamental design for an air freshener dispenser or similar article, as shown and described.

DESCRIPTION

FIG. 1 is a top plan view of an air freshener dispenser or similar article showing my new design;
FIG. 2 is a front elevational view thereof;
FIG. 3 is a bottom plan view thereof;
FIG. 4 is a left side elevational view thereof, the right side being a mirror image of the left side shown; and
FIG. 5 is a rear elevational view.

FIG. 1

FIG. 2

FIG. 3

FIG. 5

FIG. 4
